UNITED STATES PATENT OFFICE.

WILLIAM MOLENAAR, OF PATERSON, NEW JERSEY.

BILL-FILE.

1,078,452.

Specification of Letters Patent. Patented Nov. 11, 1913.

Application filed March 8, 1912. Serial No. 632,345.

To all whom it may concern:

Be it known that I, WILLIAM MOLENAAR, a citizen of the United States, residing at Paterson, in the county of Passaic and State 5 of New Jersey, have invented certain new and useful Improvements in Bill-Files, of which the following is a specification.

This invention relates to systems for keeping accounts and the like and particularly to that class of such systems in which bills, slips or the like bearing accounts or other data are held in orderly arrangement in suitable classifying devices, for instance, as in my Patent No. 883,468.

15 The general objects of this my present invention may be stated as follows: the housing of the means for holding the account or other papers within a suitable case in such a way that they will be protected from the access of fire or of unauthorized persons; the arranging of the said means within a case in a way calculated to allow their ready removal in groups or sets and at the same time secure simplicity 20 and durability and compactness of construction; the forming of the bill holders constituting units of the aforesaid bill holding means so as to facilitate the filing of the papers in such a way as to promote accuracy in the keeping of the accounts according to the preferred method (to be explained); and, finally to improve the apparatus involved so as generally to promote 25 accuracy, avoid waste of time in making entries, afford immediate disclosure of balances and keep the various accounts unexposed to the view of all except the persons having authorized access to them.

In the accompanying drawings, Figure 1 40 is a front elevation of the improved apparatus, its cover appearing partly broken away. Fig. 2 is a plan view of the case, partly in section and open, the hinged member of the cover being shown moved along 45 on its hinge; Fig. 3 is a side elevation of the apparatus, its case being closed; Fig. 4 is a side elevation of the apparatus, the case being open and a part of the case being broken away; Fig. 5 is a fragmentary view 50 in front elevation of one of the groups of bill holders; Fig. 6 is a fragmentary view in front elevation of one of the bill holders and a bill contained therein; Fig. 7 is a fragmentary view of one of the groups of bill holders, of the case and of the means 55 for holding the several bill files in the

group in compact or nested relation; Figs. 8 and 9 are perspective views of the two members of a bill holder; and Fig. 10 is a view showing in plan a part of the means 60 for holding a group of bill holders in compact disposition.

The body part *a* of the aforesaid case has a bottom, a back wall, two side walls and a front wall. It is preferably constructed 65 throughout of sheet metal and the structure forming said walls is preferably hollow throughout, as shown in Figs. 1 to 4, the double-walled structure thus produced being constructed to receive in the spaces of its 70 bottom-wall, side-wall, and back-wall portions a system of piping or tubing *b* having a threaded nipple *c* whereby to attach it to a water system and also having outlets *d* of the kind used as automatic sprinklers 75 in sprinkling systems for buildings, that is, outlets which are normally closed but which are adapted to open to release the water in the system when the surrounding temperature reaches a predetermined degree. One of these sprinkler outlets is shown within the case, at the bottom of the floor thereof, and the other is shown projecting through the cover (to be described). In case of 80 fire in the apartment containing the apparatus, the exposed sprinkler will usually serve to prevent damaging of the contents of the apparatus until the latter can be removed; the other sprinkler being inclosed, will 85 not be affected by the heat as soon as the exposed one, so that it will not release the water in the system except as a last resort.

It will be observed that the system of tubing is extended in the form of coils 90 throughout substantially the whole of the wall-space of the case, protecting the contents from exterior heat and preserving the interior outlet against release except, only, 95 the heat becomes so considerable that unless the contents were wetted they would be 100 destroyed or damaged.

The cover of the apparatus comprises two parts, *e* and *f*. The part *e* is a piece of sheet metal having side flanges *g* which overlap the side walls of the case *a* in the closed position of said part and its bottom edge is rebent, as at *h*, so as to hook into and form a hinge with the reversely rebent edge *i* of the front wall of the case. Part *e* may thus be 105 swung downwardly on said hinge into the position shown in Figs. 2 and 4, where it will form a rest or support; if it is desired, 110

it may further be removed from the case by sliding it laterally (Fig. 2) until the parts of the hinge separate. A hook *j* is pivoted to each flange *g* of the cover member *e*, being extended through a guide *k* (Fig. 2) in such manner that when the member *e* is swung outwardly the hooks engage said guides and support said member (Fig. 4). The other cover member, *f*, is likewise a piece of sheet metal having a continuous downwardly depending flange *l*, and when member *e* is closed member *f* fits like a cap over the case and member *e* holding the latter closed. Member *f* is apertured for the exposed sprinkler outlet *d* and also for a staple *m* on member *e*, the staple being adapted to receive a lock *n*.

On the floor or bottom of the case is secured a metallic strip *o* extending from one side wall to the other thereof and formed with upstanding rebends *p*; to the back wall of the case is secured a similar strip *r* formed with forwardly extending rebends *s*, coinciding with rebends *p*.

Turning, now, to the groups of bill holders, *t* is a channeled support, *u*, a series of pins or pivots connecting the sides thereof, *v* and *w* back and front bill holder members, and *x* pairs of spiral springs coiled on the pins or pivots and serving not only to press each front bill holder member against the back bill holder member but, by engaging in notches *y* of the front bill holder members, to hold each of the latter secured against lateral displacement relatively to the corresponding front bill holder member. Except as hereinafter indicated, the construction and arrangement of the parts *t*, *u*, *v*, *w*, *x* and *y* are or may be the same as in my Patent No. 1,005,451. Each group, so constructed, of bill holder members is adapted to be set in the case with the lower end of its support *t* resting against the front wall of the case between two of the projections *p*, and with the upper end of the support resting against the strip *r* between two of the projections *s*, the projections *p* and *s* holding each group against sidewise movement.

To the back wall of the case behind each group of bill-holder members is secured a bracket *z* into which is tapped a screw 2 having a swiveled head 3 to which is connected a spring 4 in turn connected with a U-shaped yoke 5 (Fig. 10) whose extremities are threaded and extended through the front bill holder member of the group of bill holders, the threaded ends of such yoke having adjusting nuts 6 bearing against the said bill holder member. Thus, means is provided whereby all of the bill holder members in each group are normally held nested or in the compact disposition shown in Figs. 3 and 4; as occasion requires adjustment may be effected by manipulating either the

70 nuts 6 or (having removed the adjoining group of bill holder members) the swiveled head 3.

75 Of course, in order to have access to the bills contained between any two bill holder members the front member is drawn back on its pivot from the rear member, so that all the forward members are, as it were, parted from the rear members, the spring 4 maintaining a tension on the forward members which will return them when released. In order that the group of members may not be unshipped from the case when this parting occurs, each group is held in place as follows: Pivoted at 7 to the back 80 wall of the case back of each group of bill holder members is a spring clip 8 whose lower end in the normal or vertical position of the clip overlaps and bears against the upper end of the support *t* and whose upper end projects slightly above the rear-most bill holder member. In this position the upper end may be used, if desired, to clamp bills or other memoranda between itself and the back wall of the case (for 85 instance, orders which are to be filled at a certain time). Upon swinging the clip 8 on its pivot toward the horizontal position, the group of bill holder members held thereby will be released and may be removed.

90 Returning, now, to the construction of the bill holder members, the rear bill holder member has slits cut into its lower edge and the part of the metal between the slits bent up forward to form rests 9 for bills 10; the front bill holder member has openings 11 to receive these rests, which are preferably long enough to still be received in the openings when the members stand separated. Further, the front bill holder member has rearwardly projecting side flanges 12 which stand relatively between upper and lower forwardly projecting side flanges 13 and 14 on the rear member when the bill holder is closed. As in my patent last referred to, 100 the rear member has a spur and the front member a corresponding opening 16. The purpose of the construction involving the parts 9 and 11 and 12, just described is to 105 engage each bill entered into the bill holder with precision. For instance, it being predicated that the sum total of amounts of purchases of bills already entered is always placed by the user on the last or foremost bill, in a definite place thereon at the right hand side thereof, if the newly entered bill should stand shifted a little to the left to expose the last figure in the sum total on the preceding bill this figure might be read accidentally as a figure in the sum to be 110 forwarded when another bill is to be entered. By extending the rests 9 far enough forward so that they enter the openings 11 in the open position of the bill holder, the bill 115 will rest squarely thereon; and (what is of 120

125 130

greater value) since it is more convenient and natural to lay the bill on the back of the forward bill holder member, between gages, such as 12 on that member, when the 5 forward bill holder member is released it will carry the bill back into absolutely true relation to those already filed.

Following a rectangular outline 17 the metal of each bill holder member, forward 10 and rear, is pressed forward to form a label holder, a slit being formed at 18 to admit the label and spurs 19 cut out of the pressed-up part of the metal to hold the label flat. The back and front bill holder members are 15 preferably both provided with labels, since if only the front member has a label the user is likely to enter a bill in the wrong place without perceiving the error—a mistake which is checked at once when the rear 20 bill holders are also labeled.

To the inside of the cover member *e* may be secured spring clips or straps 20 for holding in place a paper sheet 21 on which may be kept an index of names of customers 25 and other data should the proprietor prefer that the labels be inscribed with numbers to designate customers instead of their names, corresponding numbers being placed opposite the names in the index, as shown in 30 Fig. 2.

Having thus fully described my invention, what I claim as new and desire to secure by Letters Patent is:—

1. The combination of an inclined support *t*, a series of upstanding bill holder members attached thereto, a case receiving said support and having a back, the upper end of said support resting against said back and said case limiting forward movement of the support, and a clip pivoted to said back on an axis substantially perpendicular thereto and normally standing upright and having its lower end releasably holding the upper end of said support to said back and its other end projecting upwardly above said series of bill-holder members and serving as a means to turn the clip on its pivot out of engagement with the support, substantially as described.

2. The combination of a series of upstanding bill-holder members arranged face to face and pivoted on parallel axes in their lower portions, means for supporting said series of bill-holder members, said means 55 limiting backward pivotal movement there-

of, a substantially U-shaped yoke having its extremities projecting forwardly and respectively attached to the side portions of the foremost bill-holder at a point above its pivot, and elastic means, connecting said yoke with a part of the supporting means back of said bill-holder members, normally exerting a pull on said yoke toward said part of the supporting means, substantially as described.

3. The combination of a case closed at the bottom, back and sides and open forwardly and a cover member pivoted on a horizontal axis at the front side of and to the case, the case and cover member having interlocking hinge portions and the cover member being 70 slideable longitudinally of its axis of movement on the hinge member of the case into separated relation to the latter, substantially as described.

4. The combination, with a suitable support, substantially flat forward and rear bill holder members pivoted therein face to face and each formed of sheet material, a spur projecting forwardly from the rear bill holder member to pierce and thereby hold against movement in their own planes the bills to be filed, the forward bill holder member having rearwardly projecting lateral gages preventing sidewise movement of a bill placed between them, and elastic means normally holding the front bill holder member pressed back against the rear bill holder member, substantially as described.

5. The combination, with a suitable support, substantially flat forward and rear bill holder members pivoted therein face to face and each formed of sheet material, horizontal gaging means for the lower edge of the bill to be filed projecting from one of 95 said members toward the other, the forward bill holder member having rearwardly projecting lateral gages preventing sidewise movement of said bill when placed between said members, and elastic means normally 100 holding the front bill holder member pressed back against the rear bill holder member, substantially as described.

In testimony whereof I affix my signature in presence of two witnesses.

WILLIAM MOLENAAR.
